To all whom it may concern:

Be it known that I, Jack Shain, a citizen of the United States, residing in Newton in the county of Suffolk and Commonwealth of Massachusetts, have invented a new, original, and ornamental Design for Knitted Fabrics, of which the following is a specification, reference being had to the accompanying drawings, forming a part hereof.

In the accompanying drawings, Figure 1 is a plan view of one side of the knitted fabric of my new design. Figure 2 is a plan view of the opposite side of the knitted fabric. Figures 3 and 4 are enlarged detailed views of Figures 1 and 2, respectively.

I claim:

The ornamental design for a knitted fabric, substantially as shown.
